UNITED STATES PATENT OFFICE.

CHARLEY FOSTER AND JOHN RAYNOR, OF SOUTHWEST CITY, MISSOURI.

TRUNK FASTENING AND LASHING DEVICE.

1,066,482.

Specification of Letters Patent.

Patented July 8, 1913.

Application filed August 26, 1911. Serial No. 646,297.

To all whom it may concern:

Be it known that we, CHARLEY FOSTER and JOHN RAYNOR, citizens of the United States, residing at Southwest City, in the 5 county of McDonald and State of Missouri, have invented a new and useful Trunk Fastening and Lashing Device; and we do hereby declare the following to be a full, clear, and exact description of the invention, 10 such as will enable others skilled in the art to which it appertains to make and use the same.

This invention relates to a new and useful trunk fastening or lashing device.

15 The object of the invention is to provide a device of this nature for tying trunks, suitcases, boxes, packages, or any kind of commodity, which device comprises a number of suitable straps of any suitable material, extending about the commodity transversely and lengthwise thereof, the ends of two of the straps having hook and eye connections, while the ends of the other two straps are provided with a clasp locking device, which, as it is closed, tightens the 25 straps.

The invention comprises further features and combinations of parts, as hereinafter set forth, shown in the drawings and 30 claimed.

In the drawings, Figure 1 is a view of the fastening or tying device, showing the commodity in dotted lines. Fig. 2 is a detail view of the clasp fastening device detached, showing the parts thereof in locked positions. Fig. 3 is a view similar to Fig. 2, showing the parts in unlocked positions. Fig. 4 is a detail view of the hook 11 and the ring 9, showing the straps 7 and 8.

40 Referring to the drawings, 1, 2, 3 and 4 designate straps, which are connected to the rings 5 and 6. Connected also to the rings 5 are the straps 7 and 8. The end of the strap 8, which is arranged on top 45 of the commodity, connects to a ring 9, while the looped end 10 of the strap 7 is provided with a hook 11, designed to connect to the ring 9. The strap 7 is provided with a buckle 12, whereby the same 50 may be shortened or lengthened, in order that the strap 7 may be passed about the commodities of different sizes.

Connected to the rings 6 are the straps 55 13 and 14. The strap 13 is provided with a buckle 15, and so arranged as to permit the strap 13 to be lengthened or shortened,

so as to fit commodities of different lengths. The looped end of the strap 13 is provided with a link 16 terminating in a hook 17. This hook 17 engages a link 18, which is pivoted in the eyes of the clasp lever 19. The eyes of the clasp lever are denoted by the characters 20. The clasp lever comprises the side portions 21 and 22, the free ends of which are turned into loops 23. 60 These loops 23 fulcrum on the commodity, as the clasp lever is being closed. When the clasp lever is closed, the loops 23 hold the same closed until a locking device is locked. The portions 24 beyond the loops terminate 65 in hooks 25, which engage the eyes 26 of the wire U-shaped member 27. This wire U-shaped member is carried by one end of the strap 14, as shown. The free end of the clasp member 19 is provided with a tab 28, 70 whereby the same may be swung open. Also carried by the free end of the clasp lever 19 is a spring locking device 28a. The laterally extending portions 29 of the spring locking device engage the side portions of 75 the U-shaped member, in order to hold the clasp lever 19 in a locked position with relation to the U-shaped member, as shown in Fig. 2. To secure the spring locking device to the clasp lever, the same is coiled about 80 the clasp lever.

In tying a commodity, the straps are arranged as shown in Fig. 1 and the hook 11 is connected to the ring 9. Subsequently, the hook 17 of the link 16 is connected to 90 the link 18, after which the clasp lever is thrown in a closed position, as shown in Figs. 1 and 2, thus drawing the straps 13 and 14 taut, about the length of the commodity. The clasp lever 19 is finally locked 95 with relation to the U-shaped wire member, by throwing the laterally extending ends of the spring locking device under the side portions of the wire U-shaped member.

The invention having been set forth, what 100 is claimed as new and useful is:—

In combination, a pair of straps, a U-shaped member having an offset portion extending downwardly at one end to which one end of one of the straps is connected 105 and provided with eyes at the other end, a clasp lever constructed of a single piece of wire bent in U-shaped form, the free end portions of which terminate in offset hooks connecting the eyes of the first U-shaped member, the clasp lever having eyes intermediate its ends, a link pivoted in the eyes 110

2
of the clasp lever, a link connected by one end of the other strap and terminating in a hook to engage the link of the clasp lever, a U-shaped spring locking device the intermediate portion or arch of which is formed in coils wound about the arch of the clasp lever, thereby pivoting the locking device to the free end of said lever, the locking device having its spring arms terminating in laterally extending portions to engage the side portions of the first U-shaped member when the lever is closed, the said lever having loops adjoining the hooks adapted to bear against a commodity and so arranged with respect to the

hooks, that the straps may be drawn tight as the lever is closed, the spring locking device adapted to engage in the offset portion of the first U-shaped member to permit the laterally extending portions to engage 20 said side portions.

In testimony whereof we have signed our names to this specification in the presence of two subscribing witnesses.

CHARLEY FOSTER.
JOHN RAYNOR.
